United States Patent Office

Des. 188,343
Patented July 5, 1960

188,343

NOVELTY KEY

Bruce S. Sedley, Fairfax, Calif., assignor to Audio Tours, Inc., San Francisco, Calif., a corporation of California

Filed Dec. 23, 1959, Ser. No. 58,785

Term of patent 14 years

(Cl. D50—4)

Fig. 4.

Fig. 3.

Fig. 2.

Fig. 7.

Fig. 5.

Fig. 6.

Fig. 1 is a perspective view of a novelty key showing my new design;

Fig. 2 is a view in front elevation of the key of Fig. 1;

Fig. 3 is an end elevational view from the left of Fig. 1;

Fig. 4 is a top plan view of the same;

Fig. 5 is a view in rear elevation of the same;

Fig. 6 is a bottom plan view of the key of Fig. 1; and

Fig. 7 is an end elevational view from the right of Fig. 1.

I claim:

The ornamental design for a novelty key, substantially as shown.
